[57] CLAIM

The ornamental design for dental organizer, as shown and described.

DESCRIPTION

FIG. 1 is a front elevation of a dental organizer incorporating our design, the rear elevation being a mirror image of FIG. 1;

FIG. 2 is an end elevation of the dental organizer, the opposite end being a mirror image of FIG. 2;

FIG. 3 is an illustration of the two halves of the dental organizer when in separated position;

FIG. 4 is a plan view of the lower half of the dental organizer of FIG. 3;

FIG. 5 is a longitudinal cross-section through the dental organizer of FIG. 3;

FIG. 6 is a plan view of the top half of the dental organizer of FIG. 3; and,

FIG. 7 is an underside plan view of the lower half of the dental organizer of FIG. 3.
